UNITED STATES PATENT OFFICE

FRED F. FINCH, OF SAN FRANCISCO, CALIFORNIA

ENGINE

Application filed March 26, 1928. Serial No. 264,873.

My invention relates to improvements in engines, and it consists in the combinations, constructions, and arrangements hereinafter described and claimed.

5 An object of my invention is to provide an engine in which the customary piston is inverted and the explosion of the gas takes place within the interior of the piston. A novel water jacket is provided for cooling 10 the inside and outside of the piston.

The invention further contemplates the use of the two-cycle principle in engines, and makes use of a novel means for scavenging the interior of the piston when it is near 15 its lowermost position, injecting a new supply of fuel, such as gas, into the piston when it is at its lowermost position, compressing this gas as the piston moves upwardly and exploding this gas at the instant the piston 20 starts on its down stroke. The explosion can be effected by means of a spark plug, or the engine can work in the same manner as a Diesel engine. Moreover, the new gas admitted to the piston can be taken from the 25 crank case, which is the usual construction in a two-cycle engine, or it may be admitted from a source lying exterior of the engine. Although I have shown only one cylinder, it is obvious that as many cylinders as 30 desired may be employed.

Other objects and advantages will appear in the following specification, and the novel features of my invention will be particularly pointed out in what I hereinafter claim.

35 My invention is illustrated in the accompanying drawing forming a part of this application, in which:

The figure shows a vertical section through the engine.

40 In carrying out my invention I provide an engine block 1 having a head 2 and a crank case 3. The block 1 and the head 2 are provided with a space 4 for receiving water, this space constituting a water jacket for the 45 cylinders.

A piston 5 is slidably mounted in a cylinder 6, and this piston is inverted and has its closed end 7 disposed at the bottom of the cylinder and its open end extending upwardly. The apron or skirt 8 of the pis-

ton enters an annular recess 9. The water jacket surrounds the three walls forming this recess. In this way the inside and outside of the piston is kept cool by the water jacket. The closed end 7 of the piston moves 55 toward and away from a fixed firing head 10 during the operation of the engine.

The piston is provided with ports 11 in its skirt 8, through which the exhaust gases pass. It is further provided with ports 12 60 for receiving fresh air and with ports 13 for receiving a new charge of gas. The ports 12 and 13 are disposed adjacent to each other and near the closed end 7 of the piston. The ports 11 communicate with passageways 14, which in turn communicate with the atmosphere. In like manner the ports 12 communicate with air pipes 16 and the air in these pipes is controlled by valves 17. The valves 17 are operatively connected 65 to a crank 18 in a manner to correctly time the operation of the valves. Pipes 19 communicate with the ports 13 during a portion of the stroke of the piston and these pipes lead from a carburetor, not shown. 70

75 From the foregoing description of the various parts of the device, the operation thereof may readily be understood.

Water is kept in circulation throughout the water jacket by means of an inlet pipe 80 20 and an outlet pipe 21. It should be noted that the water jacket extends to the very bottom of the cylinder.

Assume that the piston is in the position shown and that it has received its charge of 85 new gas through the port 13 and is ready to start on its compression stroke. The new gas or fuel admitted to the engine is rich enough to permit a slight exhausting of the air through the large exhaust ports 11 on the initial upward movement of the piston and after the ports 13 have been closed and prior to the complete closing of ports 11. The up stroke of the piston will cause the port 12 to register with the pipe 16, but the valve 17 will be closed as shown and no air will enter. The spark plug 22 will ignite 90 this gas after the piston has compressed it and started on its down stroke.

95 As soon as the piston on its down stroke 100

reaches the position to align the ports 12 with the pipes 16, valves 17 will be open and air under pressure will be shot into the piston and will scavenge it of all burnt gases. 5 The ports 11 will be registering with the exhaust passageways 14, thus permitting the scavenged gas to be exhausted from the piston. A further movement downward of the piston will bring the ports 13 into registration with the pipes 19 carrying the new gas. 10 This gas will be injected into the piston under pressure and will force the greater part of the air contained in the piston out through the exhaust ports 11. The valves 15 17 close at this time. As the piston starts on its up stroke what little remains of the fresh air at the top will pass out through the ports 11 until they are closed. The valves 17 prevent any additional air from flowing into 15 the piston as the latter moves upward. The engine now repeats the cycle. This construction causes a driving impulse to be delivered to the crank shaft during each reciprocation of the piston.

20 25 The interior of the piston may be lined with a heat-resisting material 23 and the head 10 may also be lined with the same material. This material will confine the heat within the piston and will tend to prevent 30 an enormous loss of heat, which exists in practically all types of engines.

Although I have shown the ports 12 and 35 13 as being disposed one above the other, I prefer in practice to dispose the openings 12 and the pipes 16 one-quarter of a circle further around the piston cylinder.

Although I have shown and described one embodiment of my invention, it is to be understood that the same is susceptible of 40 various changes and I reserve the right to employ such changes as may come within the scope of the invention as claimed.

I claim:

45 1. A two cycle engine comprising a cylinder having a head descending thereinto so as to form an annular recess with the same, an inverted piston having its skirt slidably mounted in the recess, said cylinder and piston having exhaust ports disposed 50 at the top of the inverted piston and cylinder, air intake ports near the bottom of the piston and cylinder, and gas intake ports at the bottom of the piston and cylinder, said ports being designed to register with 55 each other during the movement of the piston, and valves cutting off the flow of air through the cylinder air ports on the compression stroke of the piston.

60 2. In an engine in which the explosion takes place within the piston, a cylinder and a piston having exhaust ports disposed at the top of the inverted piston and cylinder, air intake ports near the bottom of the piston and cylinder, and gas intake ports at 65 the bottom of the piston and cylinder, the

exhaust ports in the piston being larger than any of the other ports and registering with the exhaust ports in the cylinder while the air and gas ports in the piston successively register with their respective cylinder ports. 70

3. In an engine in which the explosion takes place within the piston, a cylinder and a piston having exhaust ports disposed at the top of the inverted piston and cylinder, 75 air intake ports near the bottom of the piston and cylinder, and gas intake ports at the bottom of the piston and cylinder, the exhaust ports in the piston being larger than any of the other ports and registering with the exhaust ports in the cylinder while the air and gas ports in the piston successively register with their respective cylinder ports, and valves for cutting off the flow of air in the cylinder air intake ports during 80 the compression stroke.

4. In a two cycle engine in which the compressing and exploding of the gas takes place within the piston, a cylinder and a piston having exhaust ports at the top of the piston and cylinder, and air inlet ports near the bottom of the piston and cylinder, all of said ports being designed to register as the piston nears the end of its power stroke for scavenging the piston of burnt gases, said cylinder and piston having gas intake ports at their bottoms designed to register after the air intake ports move out of alignment with each other at the completion of the power stroke, the exhaust ports in the piston being large enough to still register with the cylinder exhaust ports during this part of the stroke. 90

5. In a two cycle engine in which the compressing and exploding of the gas takes place within the piston, a cylinder and a piston having exhaust ports at the top of the piston and cylinder, and air inlet ports near the bottom of the piston and cylinder, all of said ports being designed to register 105 as the piston nears the end of its power stroke for scavenging the piston of burnt gases, said cylinder and piston having gas intake ports at their bottoms designed to register after the air intake ports move out of alignment with each other at the completion of the power stroke, the exhaust ports in the piston being large enough to still register with the cylinder exhaust ports during 110 this part of the stroke, and valves for closing the cylinder air ports on the compression stroke of the piston. 115
